(57) **CLAIM**

The ornamental design for a golf swing accessory, as shown and described.

DESCRIPTION

FIG. 1 is a perspective view of a first embodiment of the golf swing accessory, in an assembled configuration;

FIG. 2 is a left end elevational view of the golf swing accessory of FIG. 1;

FIG. 3 is a side elevational view of the golf swing accessory of FIG. 1, the opposite side elevational view being a mirror image thereof;

FIG. 4 is a right end elevational view of the golf swing accessory of FIG. 1;

FIG. 5 is a top plan view of the golf swing accessory of FIG. 1;

FIG. 6 is a bottom plan view of the golf swing accessory of FIG. 1;

FIG. 7 is a perspective view of the golf swing accessory of FIG. 1, in an unassembled configuration;

FIG. 8 is a perspective view of a second embodiment of the golf swing accessory, in an assembled configuration;

FIG. 9 is a left end elevational view of the golf swing accessory of FIG. 8;

FIG. 10 is a side elevational view of the golf swing accessory of FIG. 8, the opposite side elevational view being a mirror image thereof;

FIG. 11 is a right end elevational view of the golf swing accessory of FIG. 8;

FIG. 12 is a top plan view of the golf swing accessory of FIG. 8;

FIG. 13 is a bottom plan view of the golf swing accessory of FIG. 8; and,

FIG. 14 is a perspective view of the golf swing accessory of FIG. 8, in an unassembled configuration.

The broken-line disclosure of elements is understood to represent portions of the article in which the design is embodied, but which form no part of the claimed design.
